UNITED STATES PATENT OFFICE

RAY W. DUMONT, OF NEW YORK, N. Y., ASSIGNOR TO BEST & CO. INC., OF
NEW YORK, N. Y.

DESIGN FOR A DISPLAY HEAD

Application filed November 14, 1929. Serial No. 33,444. Term of patent 3½ years.

To all whom it may concern:

Be it known that I, RAY W. DUMONT, a citizen of the United States, residing at New York, in the county of New York and State of New York, have invented a new, original and ornamental Design for a Display Head, of which the following is a specification, reference being had to the accompanying drawings, forming a part thereof.

I claim:—

The ornamental design for a display head, as shown.

RAY W. DUMONT.
